(57) **CLAIM**

I claim the ornamental design for an zipline trolley with handle, as shown and described.

DESCRIPTION

FIG. 1 is a Perspective view of an zipline trolley with handle showing my new design;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken lines are for the purpose of illustrating portions of the article that form no part of the claim.

1 Claim, 4 Drawing Sheets

FIG. 1

FIG. 2
